[57] CLAIM

The ornamental design for wiper blade and frame therefor, as shown and described.

DESCRIPTION

FIG. 1 is a perspective view of a wiper blade and frame therefor, showing my new design;

FIG. 2 is an end elevational view, the opposite end

being identical thereto;

FIG. 3 is a side elevational view, the opposite side being

identical thereto;

FIG. 4 is a top plan view thereof;

FIG. 5 is a bottom plan view thereof;

FIG. 6 is an end elevational view of a second embodiment of a wherein the configuration of the blade;

FIG. 7 is an end elevational view of a third embodiment of a wiper blade and frame therefor, wherein the only difference resides in the configuration of the blade;

FIG. 8 is an end elevational view of a fourth embodiment of a wiper blade and frame therefor, wherein the only difference resides in the configuration of the blade.

FIG. 9 is a view like that of FIG. 1 illustrating a wiper blade and frame of somewhat modified form;

FIG. 10 is an end elevational view thereof (both end elevations are substantially identical);

FIG. 11 is a side elevational view thereof (both side elevations are substantially identical);

FIG. 12 is a top plan view thereof; and

FIG. 13 is a bottom plan view thereof.

FIG. 2.

FIG. 3.

FIG. 4.

FIG. 5.

FIG. 6.

FIG. 7.

FIG. 8.
